UNITED STATES PATENT OFFICE.

ERNEST R. VIBERG, OF MONTREAL, QUEBEC, CANADA.

CENTERING AND SUPPORTING DEVICE FOR TRAIN PIPES.

Application filed January 26, 1925. Serial No. 4,930.

This invention relates to the new and useful improvements in sliding carriers for air brake signal and steam heating pipe lines and is especially adapted for use in connection with the train pipe sections which are connected by couplings which automatically uncouple when sufficient strain or pull is exerted on them, a condition which frequently develops when going around reverse bends or curves, owing to the swinging motion of the cars. This uncoupling is particularly noticeable in standard cars using the American Railway Association Class "D" coupler, on account of the long wheel base and overhang of these cars.

The object of the invention is to provide a wide carrier of the class stated which will allow sufficient clearance between the coupler head and the signal and steam heating coupler to allow as much free movement of the coupler as possible while the cars are rounding curves or bends in the track.

Another object is to provide a carrier of the class stated which will oscillate with the coupler and maintain a predetermined distance between the coupler and the centers of the signal, air brake and steam heat pipe lines and also between the centers of these pipes and the rail level.

A further object is to provide a carrier of the class stated which will operate in conjunction with the coupler centering device.

A still further object is to provide a pipe line carrier which will hold the steam valve in an absolute position at all times to allow easy manipulation of the opening and closing mechanism of the valve.

A still further object is to provide a carrier which will be simple and efficient in operation.

In my invention I provide a carrier which is mounted on guides attached to the centering device. The carrier is provided with means adapted to engage with the sides of the coupler shank which, in turn, is controlled by the coupler centering device. The air brake and signal pipes which are on one side of the coupler are secured to the carrier by a clip while the steam pipe which is on the other side of the coupler is secured to the carrier by means of a pivotally mounted bracket which engages with part of the valve of the steam pipe and prevents rotary movement of the valve which remains a predetermined distance from the center of the coupler at all times and allows easy manipu-

lation of the valve opening and closing mechanism. The pipes are spaced from one another to allow free movement of the coupler when rounding curves.

In the drawings.

Figure 1 is a partial end view of a car showing my improved pipe carrier attached to the coupler centering device.

Figure 2 is a sectional elevation of the device taken on the line 2—2 Figure 1.

Figure 3 is a plan view of the centering device and the pipe carrier, and

Figure 4 is a side elevation of the steam valve support.

Referring more particularly to the drawings, 11 designates a portion of the underframing of a car body to which is attached the coupler support bar 13 by any suitable means. The centering device for the coupler 12 is secured to the coupler support by means of the bar bracket 14, the ends 15 and 16 of which are bent downwardly and are provided with apertures which form bearings 17 for the bolt 18 passing through said ends. Slidably mounted on the bolt 18 and between the bearings 17 are the centering castings 19 and 20, the upwardly projecting ends 21 and 22 of which engage with the sides of the draw bar 23, in such a manner that on any lateral movement of the draw bar, a spring 24 mounted between the centering casting bearings 25 will be compressed and will tend to bring the coupler back towards the center of the car. The spring is mounted on the bolt 18 and a sleeve 26 is placed between the spring and the bolt and between the bearings 25 to limit the movement of the coupler and to hold the spring in position. Secured to the ends 15 and 16 are the guide brackets 27 which project outwardly from said ends in the horizontal direction and are provided with closed slots 28. Slidably mounted in the slots is the pipe line carrier 29 having upwardly projecting end 30 to which are attached the air brake pipe 31 and the signal pipe 32 by means of the clip 33 which may be secured to the carrier by means of a single bolt 34. The air brake and signal pipe lines are on one side of the coupler while the steam heat pipe line 35 is situated on the other side of the coupler bar. The pipe lines may be provided with ball swivel joints 36, one of which is shown in Figure 2 to allow free movement of the ends of the pipes. The center portions of

these pipes may be secured by any suitable means to the bolster or the car framing. The end of the steam pipe is provided with a valve 37 having a hexagonal portion 38 which may be positioned above the carrier. The valve is of the usual type used for this purpose and is arranged for easy manipulation of the opening and closing mechanism. To prevent turning of the valve and also accidental operation of same a casting or bearing 39 is provided, pivotally attached to the carrier by means of the bolt 40. The bearing is provided with a recessed portion 41 adapted to engage with the hexagonal portion 38 of the valve to hold same against rotary movement. A bolt 42 is placed through the bearing to hold the valve in position. The bearing being pivotally mounted on the carrier allows the free movement of the pipe and the carrier bar while they are in operation. Mounted on and secured to the carrier is the saddle 43, the upwardly projecting sides of which engage with the sides of the draw bar and transmit any horizontal movement of the draw bar to the pipe line carrier.

Modifications may be made in the construction of the device without departing from the spirit of the invention, and such modifications may consist of forming the guides integral with the centering bracket 14 and also forming the saddle integral with the carrier. The operation of the device is very simple. On movement of the coupler bar, motion is transmitted to the pipe line carrier by means of the saddle which engages with the sides of the coupler shank. The pipes being attached to the carrier move with same and the said pipes are held a predetermined distance away from the coupler shank to allow free movement of the coupler head and to prevent same from fouling the pipe line couplers (not shown). By attaching the steam pipe to the carrier by means of the pivotally mounted bracket, allowance is made to prevent binding of the carrier in its guides. The bracket also holds the valve in its set position for easy manipulation of its closing and opening mechan-

ism. It will be seen that the pipe lines are held in position a predetermined distance from the rail level and also by providing ball joints for the pipes, free movement of their ends is ensured. The coupler shank when uncoupled is automatically brought to the center of the car by means of the centering device which, in an indirect manner, also controls the centering of the train pipe connections through the coupler bar and guides. The device is simple in construction and efficient in operation.

Having thus described my invention, what I claim is:—

1. The combination of a coupler support, a bar fixed to the underside of said support and equipped with depending terminals, a pair of brackets fixed to and projecting forwardly from the depending terminals of said bar, a pipe carrier mounted to slide in slots formed in said brackets, a member fixed to the carrier between said brackets and engageable with opposite sides of the draw bar to cause the carrier to move therewith and pipe holding means carried by the terminal portions of the carrier outwardly of said brackets.

2. A pipe carrier for draw bar supporting and centering structures comprising a pair of brackets adapted to be rigidly attached to a draw bar supporting structure to project forwardly therefrom, a pipe carrier mounted to slide through openings formed in said brackets, a U-shaped member fixed to the central portion of the carrier between said brackets with the arms of said member extending upwardly for engagement with opposite sides of a draw bar to cause the carrier to move therewith, one end of said carrier being bent upwardly at an angle to the body of the carrier and equipped with means for holding the air brake and signal pipes thereto, the remaining end of the carrier being equipped with means for securing the steam pipe thereto.

In witness whereof, I have hereunto set my hand.

ERNEST R. VIBERG.
